ration of New York

Application February 14, 1935, Serial No. 55,437

Term of patent 3½ years

To all whom it may concern:

Be it known that I, Isidore Lending, a citizen
of the United States, residing at New Bedford,
in the county of Bristol and State of Massachu-
setts, have invented a new, original, and orna-
mental Design for Hand Bags, of which the fol-
lowing is a specification, reference being had to
the accompanying drawing, forming part thereof.

Figure 1 is a perspective view of a hand bag
in a closed position.

Figure 2 is a perspective view of a hand bag,

when one of its compartments is open with the
surface grain omitted.

Figure 3 is a view similar to that of Figure 2,
but shows the opening of the other compartment
of the hand bag.

The back of the hand bag shown in Figure 1 is
substantially the same as the front.

I claim:

The ornamental design for a hand bag, as
shown and described.

ISIDORE LENDING.
